CARRYING CASE FOR A CUSHION

Florence Sheldon, 570 N. Kenmore Ave.,
Los Angeles, Calif.

Filed June 26, 1962, Ser. No. 70,694

Term of patent 14 years

(Cl. D15—8)

FIG. 1.

FIG. 2.

FIG. 3.

FIG. 4.

FIG. 5.

FIG. 6.

FIG. 7.

FIG. 8.

FIG. 9.

FIG. 1 is a perspective view of a carrying case for a cushion embodying the new design of my invention;

FIG. 2 is a front elevational view of this article in a folded carrying position;

FIG. 3 is a side elevational view of this article in a folded carrying position;

FIG. 4 is a top elevational view of this article in a folded carrying position;

FIG. 5 is an elevational view showing the outside of this article in an unfolded or spread out configuration;

FIG. 6 is an elevational view showing the inside of this article in an unfolded configuration;

FIG. 7 is a side view of this article in an unfolded, expanded configuration;

FIG. 8 is an end view of this article in an unfolded, expanded configuration; and

FIG. 9 is another end view of this article in an unfolded, expanded configuration.

I claim:

The ornamental design for a carrying case for a cushion, substantially as shown.
